W. M. DAVIDSON.
CRUSHER AND PULVERIZER.
APPLICATION FILED NOV. 3, 1921.

1,420,021.

Patented June 20, 1922.

UNITED STATES PATENT OFFICE.

WILLIAM M. DAVIDSON, OF ST. LOUIS, MISSOURI, ASSIGNOR TO WILLIAMS PATENT CRUSHER AND PULVERIZER COMPANY, OF ST. LOUIS, MISSOURI, A CORPORATION OF MISSOURI.

CRUSHER AND PULVERIZER.

1,420,021.

Specification of Letters Patent. Patented June 20, 1922.

Application filed November 3, 1921. Serial No. 512,487.

To all whom it may concern:

Be it known that I, WILLIAM M. DAVIDSON, a citizen of the United States, residing at St. Louis, State of Missouri, have invented certain new and useful Improvements in Crushers and Pulverizers, of which the following is a specification.

This invention relates to certain new and useful improvements in crushers and pulverizers the peculiarities of which will be fully described and claimed hereinafter.

The main object of my invention is the provision of adjustable inset cutters forming extended wall surfaces of recesses in a curved horizontal wall the inner serrated face of which lies adjacent to rotary hammers of a crusher or pulverizer; second, of means detachably connected to said inset cutters for adjusting them from the outside; and thirdly of reversible adjustable inset cutters in connection with cove recesses.

In the accompanying drawing on which like reference letters indicate corresponding parts, Fig. 1 represents a partial section elevation on a vertical plane across the shaft of a machine exemplifying my invention; Fig. 2 a plan view of a slidably adjustable portion of said machine partly broken away on the line 2—2 of Fig. 1 to show an independently adjustable inset piece forming a cutting edge and its detachable adjusting means; and Fig. 3 an inside face view of such cove recesses with adjustable cutting edges, and the sides of the casting in section.

The letter A designates a shaft carrying discs B or other means for mounting pivoted hammers C forming a rotor within casing walls D including a hopper E. On the inner face of said casing and opposite the ends of said hammers are formed a series of recesses preferably consisting of elements provided with plane surfaces, such as a curved surface F that acts to deflect the material driven into the recesses by the hammers so that it passes inward over a radial surface G that forms a cutting edge by intersecting in an acute angle with the following surface H in the next adjacent recess. The deflecting surface F precedes and blends with the radial surface G. This

surface H precedes the curved surface F in each recess. The intersection of the radial surface G and the next following surface H is provided with a slot extending outward adapted to receive an inset piece, preferably formed of a flat bar of a width several times its thickness, and beveled on its side edges to form double reversible cutting edges co-operating with said hammers in the reduction of material. The top of each piece forms part of the radial surface R opposing said hammer and the inner beveled edge coincides with the surface H following the cutting edge. Between the beveled edges and preferably midway are located holes through the thin dimension of the bar in which fit the hook ends of threaded hook bolts I that extend outward through holes in the casing and have nuts or other means for fastening the bolts in place. The hook ends of the bolts are located in holes J, open at their inner face and below or near the cutting edge of each serration, so that the bolts may be engaged with the bars and then slipped through the matching holes in the casing while the bars slide into the slots at the intersecting planes of the recesses. When the inner edge is worn off, the bolts may be loosened and the bars removed from the hook ends and reversed and replaced in the slots. The cutting edge can likewise be adjusted toward or away from the hammer circle by slackening off the bolts so as to put a filler K behind the outer edge of the piece, and then tightening the bar against it by the nuts and bolts. The cutting edges may be adjusted collectively by mounting a portion of the casing having recesses, on a slidable block L having adjusting screw M.

I claim:

1. In a grinding mill, a wall having a curved inner face provided with recesses therein, in combination with inset pieces, each having an opening therein and reversible cutting edges adapted to form an extension of the recess walls, and adjusting means for said inset pieces, each having one end thereof engaging in said opening, and the other end extending beyond said wall.

2. A machine of the character described

comprising a rotor having a curved wall concentric with said rotor, the inner face of said wall having a casing, a series of recesses located adjacent to the operative circle of 5 said rotor and having slots at the inner edges, inset flat bar pieces having reversible cutting edges and holes midway between said

edges, hook bolts engaging the holes in the middle of said pieces and extending outside said wall, and means to hold said bolts in 10 any adjusted position.

In testimony whereof I have affixed my signature.

WILLIAM M. DAVIDSON.
